UNITED STATES PATENT OFFICE.

BLOOMFIELD H. HOWARD, OF WASHINGTON, DISTRICT OF COLUMBIA, AND ERNEST J. TURNER, OF PITTSBURGH, PENNSYLVANIA.

FEEDER FOR INGOT-MOLDS.

1,394,415.

Specification of Letters Patent.

Patented Oct. 18, 1921.

Application filed October 1, 1920. Serial No. 414,060.

To all whom it may concern:

Be it known that we, BLOOMFIELD H. HOWARD and ERNEST J. TURNER, citizens of the United States, residing, respectively, at 5 Washington, District of Columbia, and Pittsburgh, in the county of Allegheny and State of Pennsylvania, have invented certain new and useful Improvements in Feeders for Ingot-Molds, of which the following is a 10 specification.

Our invention relates to improvement in feeders for ingot molds.

The object of our invention is to provide a 15 feeder for ingot molds which keeps the upper end of the ingot in a heated state and practically eliminates blow holes or cavities or what is known as piping in the upper portion of the iron or steel ingot and also prevent segregation and thus produce an ingot 20 homogeneous throughout in both structure and material.

Another object of our invention is to provide a feeder of this character which can be 25 readily applied to any form of plain top ingot mold and thus giving it a large range of utility and at the same time providing means whereby the feeder can be readily removed from the upper end of the mold without injury to the ingot.

30 A still further object of our invention is to provide a cheap, simple and effective feeder of this character having certain detail of structure and combination of parts herein-after more fully set forth.

35 In the accompanying drawings;

Figure 1 is a vertical sectional view of an ingot mold showing our improved feeder applied thereto.

Fig. 2 is a top plan view of Fig. 1 showing 40 the inner sleeve or shell made in four sections.

Fig. 3 is a vertical sectional view of a similar ingot mold showing a modified form of feeder applied thereto.

45 Fig. 4 is a vertical sectional view of a different form of ingot mold showing a further modification of feeder applied thereto.

Fig. 5 is a vertical sectional view of another form of ingot mold showing a still further modification of our invention applied thereto.

Fig. 6 is a vertical sectional view partly broken away showing a still further modification of our invention.

Fig. 7 is a sectional view partly broken

away showing a further modification of our invention.

Referring now to the drawings 1 represents an ingot mold, which as shown has its walls diverging toward the upper end but while we have shown this form of mold it will be understood that any form of our feeder can be applied to any of the various forms of molds shown in the different figures of the drawings. The feeder in each and all of the forms comprises an inner sheet metal sand retaining sleeve 2, which as shown in Fig. 1 of the drawings is made of a number of pieces having its edges secured together in any desired manner or the several parts 60 could be separated slightly and the spaces closed by fire clay or by strips of paper put on the outside of the inner sleeve. In the form shown in Fig. 1 the inner sleeve 2 adjacent its lower end is provided with an 65 outwardly extending flange 3 preferably formed integral therewith. This flange as shown is formed by crimping a beading thereon or could be formed by securing a flange thereto made of a separate piece of 70 metal. This flange could be in the form of a straight band or an L-shaped piece of metal or band. The outer periphery of the inner collar is of a diameter equal to the diameter 75 of the bore of the mold so that it will closely fit the same as at 5, with the flange 3 resting upon the upper edge 6 of the mold. Placed upon the upper edge of the mold at its outer edge, is a cast iron or steel sleeve 7 of a thickness considerably greater than sheet metal 80 sleeve 2. The diameter of the outer sleeve is greater than the diameter of the inner sleeve, leaving an annular space 8 between the sleeves 2 and 7. When the outer sleeve 7 has been properly placed upon the upper edge 85 of the mold spaced from the inner sleeve 2, the space 8 is filled with sand or other refractory material which holds the outer sleeve 7 against lateral movement on the mold, as the inner sleeve is held against lateral movement as heretofore described.

From the foregoing description it will be seen that the feeder is of a considerable thickness and the sand becomes intensely heated by the molten metal and remains heated for 105 a considerable length of time, thus preventing the rapid cooling of the ingot and prevents piping, as heretofore set forth and as is well understood by those skilled in the art. The molten metal of the ingot fuses the inner 110

sheet metal sleeve 2 and forms a part of the ingot. While sand or other refractory material becomes intensely heated yet it protects the outer cast iron sleeve against excessive 5 heat and when the ingot has cooled and hardened the outer sleeve can be lifted from the mold allowing the sand to fall on the outside of the mold.

While in some of the figures of the drawings we have the inner sleeve 2 of a single sheet of metal, it will be understood that the same can be made in several parts as shown in Fig. 2 of the drawings. In this event the cracks or spaces between the sections can be 10 filled with fire clay to prevent the sand from running into the mold or a sheet of paper could be placed against the outer face of the sleeve 2 to cover the spaces to prevent the sand from running into the mold.

20 In the modification shown in Fig. 3 of the drawings we provide a holding member 9 for the inner sleeve 10. This holding member comprising a cylindrical portion adapted to closely fit the bore of the mold 25 and having at its upper end a lateral flange 10' resting upon the upper edge of the mold and whereby it is supported against vertical and lateral movement. The upper edge of the holding member 9 is provided with an 30 annular groove or channel 11 of a depth equal to the thickness of the inner sheet metal sleeve 10 and adapted to receive the lower end of the said sleeve, whereby the bore of the holding member and the inner 35 sleeve are in the same vertical plane. In this form the outer sleeve and sand are arranged the same as in Fig. 1 of the drawings and need not be described.

In the modification shown in Fig. 4 of the 40 drawings we have shown a different form of mold in which the walls are parallel but it will be understood that each and all of the modifications are adapted to be used on any of the different forms of molds. In this 45 modification we have provided a sleeve holding member 14 in the form of a ring, having a laterally extending flange 15 intermediate its upper and lower ends. This flange rests upon the upper edge of the mold and the 50 portion 16 below the flange closely fits the bore of the mold. The inner sleeve 18 closely fits the portion above the flange with its lower end resting upon 15. The flange 15 is shown formed by crimping but the same could be made in a separate piece. The sand 20 and the outer sleeve 19 are arranged the same as in Fig. 1.

In the form shown in Fig. 5 of the drawings we provide a holding member 21 for the inner sleeve and which comprises a flat ring like member 22 resting upon the upper edge of the ingot mold and having a downwardly bent flange 23 closely fitting the bore of the mold. The lower end of the 60 flange is bent upwardly as indicated at 24

leaving the space 25 for the reception of the lower end of the inner sheet metal sleeve 26. The outer cast metal sleeve 27 and the sand 28 are arranged the same as heretofore described.

70 In the form shown in Fig. 6 of the drawings we have provided the lower end of the inner sheet metal sleeve 29 with the upwardly bent portion 30 adapted to closely fit the bore of the mold 31 and the upper 75 end of said upwardly bent portion provided with a lateral flange 32 resting upon the upper edge of the mold and whereby the said sleeve is held against lateral and vertical movement.

80 In the modification shown in Fig. 7 of the drawings the inner sleeve is perfectly plain at its lower end and engages the taper of the bore of the mold and supported thereby. The outer sleeve 34 like in the 85 other forms rests upon the upper edge of the mold 35.

Having described our invention, what we claim and desire to secure by Letters Patent is:

90 1. A feeder for ingot molds adapted to be removably supported by the upper end of the mold, and having an annular refractory material receiving channel open at its upper end and its lower end closed by the upper end of the mold.

95 2. A feeder for ingot molds comprising two disconnected sleeves adapted to rest upon the upper end of the ingot mold and forming an annular refractory material receiving channel closed at its lower end by the upper edge of the mold.

100 3. A feeder for ingot molds comprising two disconnected sleeves one of sheet metal and the other of relatively thicker metal 105 adapted to rest upon the upper edge of the mold and forming an annular refractory material receiving channel closed at its lower end by the upper edge of the mold.

110 4. A feeder for ingot molds, comprising two disconnected sleeves, the inner sleeve extending into the bore of the cylinder of the mold and having an annular flange resting upon the upper edge of the mold holding it against vertical movement, and the second sleeve resting upon the upper edge of the mold and held against lateral movement by a filling of refractory material between it and the inner sleeve.

115 5. A feeder for ingot molds, comprising an inner sheet metal sleeve adapted to extend into the bore of the mold and having positive means for supporting it therein, and a second sleeve of a thickness considerably greater than the inner sleeve and disconnected therefrom and resting upon the upper edge of the mold and held against lateral movement by a filling of refractory material between it and the inner sleeve.

120 6. A feeder for ingot molds comprising a

thin inner sleeve supported against lateral and vertical movement within the bore of the mold, and a relatively thicker sleeve separate from the inner sleeve and resting upon the upper edge of the mold and held against lateral movement by a filling of refractory material between it and the inner sleeve.

7. A feeder for ingot molds, comprising an inner fusible metal sleeve supported upon the upper end of the ingot mold, an outer

sleeve surrounding the inner sleeve and supported by the upper end of the mold and forming a refractory receiving channel between them having its lower end closed by the upper edge of the mold. 15

In testimony whereof we affix our signatures.

BLOOMFIELD H. HOWARD.
ERNEST J. TURNER.
